UNITED STATES PATENT OFFICE.

JOSEPH ROY, OF CLEVELAND, OHIO, ASSIGNOR TO AMERICAN STOVE COMPANY, OF ST. LOUIS, MISSOURI, A CORPORATION OF NEW JERSEY.

OVEN FRONT FRAME, DOOR, AND COOPERATING PARTS.

Application filed March 9, 1926. Serial No. 93,407.

This invention relates to improvements in oven front frames, doors and cooperating parts, the objects of which will be herein-after specified.

- 5 One object of the present invention is to so construct the oven front frame and the oven doors that when the latter are closed, the frame and the doors are flush with each other.
- 10 A further object of the present invention is to so construct the front frame and the oven doors as to permit the application to them of hinges which are sealed.

15 A further object of the invention is to so construct the front frame and the oven doors and to provide them with a latch that is invisible when the doors are closed.

20 A further object of the invention is to so construct the said front frame and oven doors that the whole space of the frame is occupied by the doors, thus eliminating the usual front cross bar between the oven doors.

25 Further objects of the invention will appear from the following description.

25 In the accompanying drawings:—

Figure 1 is a perspective view of the front of an oven with our improved front frame and oven doors.

30 Figure 2 is an enlarged inside view of the front frame and oven doors, showing therein the hinges and the cross frame that is invisible from the front.

35 Figure 3 is an enlarged central sectional view taken on the line 3—3 of Figure 4.

Figure 4 is a horizontal sectional view on the line 4—4 of Figure 2.

40 Figure 5 is a central sectional view on the line 5—5 of Figure 4.

Figure 6 is a sectional view on the line 6—6 of Figure 7.

45 Figure 7 is a sectional view on the line 7—7 of Figure 6.

Figure 8 is a sectional view through one side of the frame and the door showing a modification.

50 Figure 9 is a detached inner elevation of the hinge member B, the parts being in the position assumed when the door is closed.

Figure 10 is a similar view of the hinge member B with the parts shown in the position assumed when the door is open.

55 Figure 11 is a detached perspective view of the hinge pintle members in disassembled relation.

Figure 12 is a horizontal sectional view

through the oven door handle and the oven door.

Referring now to the accompanying drawings, A indicates the front frame, 1 the door for the upper portion of the oven and 2 the door for the lower portion of the oven. Ordinarily the upper portion is used for baking purposes and the lower portion for broiling and similar purposes. By examining Figure 1 it will be noted that the doors 60 1 and 2 are flush with the face of the frame A, and it will also be noticed that the hinges and latches are absolutely sealed. There are no working parts of the doors except the handles that are visible. 70

The front of the frame A in cross section is approximately U-shaped as shown in Figures 4, 7 and 8. It comprises the front portion or leg 3 with its outside right angular wall 4 and its inner right angular side or 75 leg 5. Attention is directed to the fact that the inner leg 5 of the front frame is made considerably deeper than the outer side or leg 4, whereby room is provided for a hinge B that is located substantially wholly within 80 the U-shaped front frame.

It will also be noted that the front frame A has a depression or inwardly extending right angular part 6 which is of a depth corresponding to a peripheral flange portion 7 85 that is formed on the doors 1 and 2 (Figures 4, 7 and 8) whereby when the doors are closed their outer faces are flush with the front or face part 3 of the frame A.

Each of the doors 1 and 2 comprises its 90 outer face portion, the flange or bent portion 7 and a leg portion 8 extending at right angles to its outer face. The said doors comprise the outer face or panel portion formed as described and an inner lining 9 which 95 has a right angular part 10 that telescopes with the part 8 of the door. This lining 9 and the part 8 of the door are bolted together by bolts 11 that pass through the part 8 of the door and the part 10 of the 100 lining. This construction makes the door and its lining separable. It will also be noted that the doors are of considerably less depth than the width of the leg 5 of the frame A. By reference to Figure 4 it will 105 be seen that the right angular portion 6 forms a step portion 12 against which the flange 7 rests when the door is closed.

For the purpose of permitting of the assembling of the door, its lining and the hinge 110

B, this front frame has its leg portion 5 pressed outward for the hinge B as shown at 13. This enables the door face or panel, the lining therefor, and the hinges B to be 5 conveniently assembled. Furthermore the flange 5 adds strength and rigidity to the whole frame.

The frame A as shown has its top and side and front flanges made of a straight continuous piece, the flange 3 thereof being notched as at 14 and bent to form the angular frame. As here shown its lower part 15 is formed of a separate angular piece, but I desire to be understood that the whole frame may be 15 formed from a straight U-shaped piece which will be notched as at 14 for the purpose of enabling it to be bent in angular form. The lower piece 15 being separate, the lower ends of the flange 3 extend at the inner side of the part 15 as shown in dotted lines and the parts are attached by means of suitable screws or bolts 16.

Referring now to the hinge construction, the linings 9 of the doors have their flanges 25 10 provided with openings 11 and suitably spot welded or otherwise secured to the inner side of the flanges 10 of the lining is a member 17 having at its lower end an angular opening 18 for receiving the turning portion 30 of the hinge B which will now be described.

The hinge comprises a vertical member 19 that is bolted to the inwardly flared portion 13 by means of suitable fastening elements 35 20 which are located above and below the pintle or turning member 21. This pintle has an intermediate and large portion 22 which is made in the form of a cam, the front and rear edges 23 of the cam 22 being flat 40 and the top and lower edges 24 being curved. The cam or enlarged portion 22 rests into an upwardly extending cavity 25 of the member 19, said member being enlarged outward as at 26 to enable the cavity to be formed. 45 This enlarged portion 26 is provided with an opening 27 that has its inner end communicating with the cavity and its outer end open. Passing through this opening 27 there is an extension 28 which is round. The extremity 29 of the extension 28 projects beyond the outer end of the opening 27. This extension 28 receives a member 30, the opening in the said member 30 and the extension 28 being oval or angular as shown at 31, 50 whereby the member 30 is held on the extension against rotation. Formed in the upper portion of the member 30 is an opening 32 that receives the lower end 33 of a coil spring 34, the upper end 35 of the coil spring being attached to an integral projection 36 at 60 the upper end of the member 19.

From the foregoing description it will be observed that the hinges are located between the inner flange 5 and the outer flange 4 65 whereby the said hinge is absolutely con-

cealed. It will also be observed that the cam 22 and its connected parts are carried by the member 19 since the member 30 being on the outer extremity 29 holds the said cam and its parts to the member 19. The cotter pin or other device 37 may be used to hold the member 30 on the extension 29.

In operation the angular inner end 21 is in engagement with the angular opening 18 of the member 17, and when the door is 70 opened, the spring 34 pulls on the member 30 tending to close the door, and when the door is moved to its horizontal position, then the straight portions of the cam 22 will engage the straight portion 24' and lock the door in 75 its horizontal position, the said spring not being sufficiently strong to close the door.

In placing the door and the hinge in position with respect to the frame A, the door will be placed in a vertical position in the frame and then the hinge which includes the member 19, cam 22, etc., has its angular end 21 inserted through the opening 18, when the part will be fastened to the inwardly bulged part 13 by means of suitable bolts or 80 other suitable elements 20. When the hinge portion is in place then the angular end 21 serves to hold the door in position and all of the parts are absolutely concealed.

For the purpose of holding the door closed 95 an improved latch is used. This latch comprises a lever 39 which is intermediately pivoted at 40, its inner end being shaped to form a weight 41, that holds its outer end 42 elevated, the outer end 42 carrying a lip 43 which is suitably shaped for engaging in an opening 44 that is formed in the flange 5 of the frame A. For the purpose of strengthening this opening a suitable member 45 is bolted to the flange 5 and the said members 100 and opening registering with the opening 44. The intermediate pivotal point 40 is supported by a member 46 that depends from the flange 10, the said member being fastened to the lining 9 by the pivotal bolt 40 and at 105 its opposite end by a bolt 47.

Thus far we have been describing the latch and its cooperating parts that may be used on the upper door. The latch used on the lower door is exactly the same as that described on the upper door. However the part that engages the lip 43 of the latch for the lower door is different. Attention is called to the fact that a horizontal member 48 extends across between the inner flanges 120 5 of the frame A, said member having its ends preferably spot welded to the said flange. This member 48 has its upper and lower edges 49 turned inward for giving the member sufficient strength. It will be noted 125 that the edges 7 of the doors 1 and 2 form a space between them and a suitable curved member 50 is located in this space. The free end of the member 50 lies in the proper position for the lip 43 of the latch 39 to engage, 130

and the opposite or inner end of the member 50 is suitably fastened to the member 48 by means of a bolt 51.

From the above description it will be understood that the construction does not contain the usual horizontal strip between the edges of the doors and hence the hinge member 48 is located inside of the doors and is supported in such a position that it does not interfere with the closing of the doors, while at the same time it furnishes a support for the curved member 50. The member 48, it will be understood, gives additional strength to the frame A.

It will be understood that the lip 43 of the latch is of such a shape as not to make a positive fastening, whereby when the door is pulled, it will readily open, but at the same time the latch serves to hold the door closed.

The action of the latch of course is by gravity due to the weighted end 41.

In my construction I desire to call attention to the construction of the handle 51 and the method of fastening it in position. The handle is made up of three parts, the part 51 preferably is constructed of enamel and the two end parts 52. The outer ends 53 have their inner sides hollow to receive the ends of the part 51 while the inner ends 54 are made integral with the parts 52. Spot welded or otherwise attached to the lining 9 are cup-shaped members 55, and screws 56 pass outward through the lining 9, the cup portion facing the door and another screw threaded opening 57 in the enlarged ends 54 opposite the parts 52. Therefore the handles have an interior connection which when the door is open only the bolts 56 are visible, but when the doors are closed the fastening parts are invisible. The function of course of the cup-shaped parts 55 is to form separating elements for the lining and the door against which the screws will tightly clamp the lining and door and the inner ends of the parts 52.

Attention is directed to the fact that the outer members 1 and 2 of the doors may be detached from the lining 9 by loosening the bolts 11 and 56, which will permit the outer parts or panels to be removed, by sliding them outward, the opening 58 having its outer end 59 open to permit the pintle 21 to pass through it.

For the purpose of strengthening the lower portion of the inner wide flange 5 of the frame A a cross member similar to 48 will preferably be applied to that portion of the frame.

Instead of forming the doors with the flange 7 to form a stop for the doors, the said flange may be omitted, in which case the frame A will have its flange 5 with a tapered bend 6', made at a distance from the part 3 equal to the thickness of the door, as shown in Figure 8. In such construc-

tion the inner edge of the door will engage the part 6' as will be readily understood for forming a limit to its inner movement.

In Figure 1 the side wall 60 and the top 61 will of course be constructed as is usual in ovens, and the part 15 will be extended to the left any desired distance in making the complete range.

By reason of the cam portion 22 having the two flat portions 23' and 24', the latch members will act at either side of the door to serve to hold the door in a horizontal position when it is open. By this it is meant that the hinges for opposite sides of the door are exactly alike and they may be placed at either side of the door and perform the above function.

I do not desire to limit myself to the details of construction that have been here shown and described, since they may be varied without departing from the spirit and scope of the invention so long as they are within the scope of the appended claims.

Having described my invention, what is claimed and desired to secure by Letters Patent of the United States is:—

1. An oven having a front frame essentially U-shaped in cross section, a door having a face portion with a lateral flange fitting within the frame, a hinge portion located within the frame and having its inner rotatable end angular and fitting in an angular opening in the flange of the door, whereby said hinge is concealed. 95

2. An oven having a front frame essentially U-shaped in cross section, a spring hinge located within the said frame, the rotatable part of the hinge extending in beyond the frame, of a door having a front part and a flange fitting within said frame, the flange having an opening, the extending part of the hinge passing through the said flange and locked therewith, whereby the hinge acts as described. 105

3. An oven having a front frame which is essentially U-shaped in cross section, a hinge essentially located within the frame, a door having a flange fitting within the frame, the flange having an opening and the hinge having an extension within the opening for the purpose described. 115

4. An oven having a front frame, a door having a flange fitting within the frame, a latch member secured to the door, the flange of the door having an opening and a hinge having a projection fitting within the flange opening for the purpose described. 120

5. An oven having a front frame, a hinge member secured to the inner portion of the said frame, a door having a flange fitting within the frame, said flange having an opening and a hinge provided with an extension fitting within the said opening, the hinge extension locked within the flange against rotation, whereby when the door is 130

opened or closed the said hinge member is rotated.

6. An oven having a front frame, a door provided with a flange fitting within the front frame, a rotatable hinge member connected with the frame and having an extension passing through the said door flange, said extension and the door flange locked against rotation, the said hinge member having a cam whereby when the door is opened said cam forms a lock for holding the door in substantially horizontal position.

7. An oven having a front frame, a hinge portion connected to the said frame, a door having a flange fitting within the frame, the hinge having an extension passing through the flange, the extension locked against rotation to the flange and the hinge having at each side a flat portion whereby it can be used at either side of the door and serve to hold the same in a horizontal position when open.

8. An oven having a front frame, a hinge connected to the said frame, a door having a flange fitting within the frame, a member located at the inner side of the flange and having an opening, the hinge member having an extension passing through the said flange, and the said opening, the opening and the extension constructed to prevent relative rotation of the parts for the purpose described.

9. An oven having a front frame, a hinge member secured to the front frame, a door having a flange fitting within the frame, a hinge secured to the frame and having a rotating member, the rotating member extending through the flange, a member attached to the inner side of the flange having an opening to receive the said extension, the hinge having a double acting cam whereby it may be used at either side of the door to serve to hold it in a horizontal position when open.

10. An oven having a front frame angular in cross section, a vertically extending member secured to one side and within the frame, the lower end of the member having an outwardly extending recess, a cam member located in the recess, a door having a flange fitting within the frame, a cam member having an extension locked against rotation to the flange, the cam having an end extending outward through the lower end of the vertical member, a spring having its lower end locked with the cam member and its upper end extending to the upper portion of the vertical member, the parts operating as described.

11. An oven having a front frame essentially U-shaped in cross section, a vertically arranged member secured to the inner leg of the frame, the lower end of the member bulged outwardly and having a recess, a rotatable member passing through the recess, a cam member within the recess having a flat portion adapted to engage the wall of the recess, a spring connected with the outer end of the cam portion, a door having a flange fitting within the frame, the cam having an inward extension passing through the flange and locked against relative rotation with the parts operating as described.

12. A front frame for an oven essentially U-shaped in cross section, a door having a flange fitting within the frame, the inner wall of the said frame bulged outward about the lower end of the door, a member secured to the outer side of the bulged portion, said member carrying a rotatable element, said element having its inner end passing through the door flange and locked thereto against rotation, the outer end of the rotatable element extending outside the member and a spring having its end connected therewith for the purpose of holding the door in closed position.

13. An oven having a front frame, a door consisting of a front panel and a lining, a hinge member connected with the frame and engaging the door, a gravity latch connected with the lining and having a lip extending beyond the edge of the lining, said frame provided with an opening to receive the said lip of the latch for the purpose described.

14. An oven having a front frame, a hinge attachable to the front frame, a door fitting within the frame and having an opening, the said hinge having a projecting rotatable member adapted to pass through the said opening, the said projecting portion fitting the said opening and held against rotation therein, the said hinge being removable and detachable.

15. An oven having a front frame, an oven door fitting within the angular frame and having its outer face flush with the outer face of the frame, the door having an opening located at the inner side of its outer face, a hinge member adapted to be attached and detached from the frame, said hinge provided with a projecting member adapted to be inserted and withdrawn from the door opening, the parts operating for the purpose described.

In testimony whereof I hereunto affix my signature.

JOSEPH ROY.
